UNITED STATES PATENT OFFICE.

FRANK McMURRAY SAWYER, OF LOS ANGELES, CALIFORNIA.

WALL CONSTRUCTION.

1,378,139.

Specification of Letters Patent. Patented May 17, 1921.

Application filed March 24, 1919, Serial No. 284,604. Renewed October 12, 1920. Serial No. 416,512.

To all whom it may concern:

Be it known that I, FRANK McM. SAWYER, a citizen of the United States, residing at Los Angeles, in the county of Los Angeles 5 and State of California, have invented certain new and useful Improvements in Wall Constructions, of which the following is a specification.

This invention relates to improvements 10 in wall construction and slabs for forming the same, and has for its particular object to provide a wall formed of standardized units, the units being of such shape that they can be molded in the type of plural molds 15 well known in the art.

Another object is to provide a wall construction which can be erected without the use of skilled labor, accomplishing the same by the use of concrete slabs formed with 20 interlocking portions, and in a manner of arrangement that will hold secure against displacement when being erected, wherein the pressure of the poured concrete in the stud sections will further interlock and bind the 25 members together.

These and other objects hereinafter set forth are attained by the means illustrated in the accompanying drawing, in which:—

Figure 1 is a perspective view of a portion of a wall shown during the course of erection.

Fig. 2 is a vertical cross-section through one of the stud sections of the wall.

Fig. 3 is a cross section on the line 3—3 of Fig. 2.

Fig. 4 is a detail perspective view of one of the longitudinal or facing slabs.

Fig. 5 is a like view of one of the key slabs, and

Fig. 6 is a detail view showing a modified arrangement of the facing slabs and a portion of a key slab in position detached from the facing slabs.

Similar reference numerals in all of the figures of the drawing designate like parts.

From Fig. 1 of the drawing, it will be observed that a hollow wall construction is provided having inner and outer courses which are bound together with transverse key-members, said key-members being arranged in a manner to form at intervals along the wall relatively narrow vertical spaces which are filled with concrete to provide solid stud sections.

The slabs 10 and 11 forming the outer and inner facings of the wall respectively,

are laid in horizontal courses, the slabs in alternate courses being staggered relative to the adjacent courses. Each of these longitudinal slabs are formed with one horizontal bevelled edge 12, preferably the top horizontal edge, the bevel extending downwardly and outwardly from the inner side of the slab, and on the inner side of each slab, at the lower corners thereof, are formed recesses 13 which are adapted to receive the locking projections 14 of the transverse stud-slabs 15.

Each of the recesses 13 is formed with a top wall which is inclined upwardly from the edge of the slab, as shown at 16, and is also inclined upwardly from the inner side of the slab, as shown at 17, thereby forming an undercut top side for each recess. The top edges of the locking projections 14 of the slabs 15 are bevelled to correspond to the top walls of the recess 13, so that when the projections are inserted in the recess, the slabs are prevented from slipping relative to each other. The recesses 13 are formed considerably wider than the thickness of the transverse slabs, so when the slabs 15 are positioned against the rear wall of the recesses 13, a large portion of the recesses in front of the projections 14 remains unfilled until the concrete is poured in the stud spaces, when it fills the balance of the recesses and forms an abutment in front of each of the projections 14. The ends of the slabs 10 are keyed to the stud filling owing to the undercut top wall of the recesses, thus securely binding the parts together, and the pressure of the poured concrete in the stud sections exerts a force against the inclined top wall of the recesses with a tendency of bringing the longitudinal slabs in direct compression endwise. In alternate courses the center of the longitudinal slabs are located at the stud sections, and to further bind the concrete column or stud to the side walls, a recess 18 is formed at the center of the lower edge of each of the slabs 10 and 11, and provided with an undercut top wall which will key the center of the slabs 10 and 11 to the stud members, and thereby eliminate all tendencies of the wall to separate or give way under loads.

The key slabs 15 are preferably formed substantially twice as high as the side slabs 10 and 11, so that alternate pairs of key slabs 15 are staggered in relation to the adjacent pairs, and the height of each of

- the key slabs is such, that with the lower edge of the key slabs resting on top edges of the longitudinal slabs, the top edges of the key slabs will not reach the plane of the top edges of the side slabs of the course positioned next above, thus none of the key slabs will rest on the key slabs lying below, and the side slabs being hung on the projections 14, and said projections being slightly higher than the height of the recesses, the lower edges of the side slabs will not rest directly upon the top edges of the side slabs below. This arrangement keeps the wall in perfect alinement.
- 15 This construction provides a wall whose units are thoroughly bonded together in a substantial manner, and with the side slabs arranged in break-joint relation, and also with the key slabs in break-joint relation with each other. The stud sections are formed of a suitable size to carry the loads desired, and said stud sections being located at intervals provide hollow walls between the stud sections, the whole forming a wall of great strength and desirability owing to the minimum amount of material necessary to obtain desired results. The surfaces of this wall can be finished in any desired manner.
- 30 It will be observed from Fig. 6 of the drawing, that the slabs can be arranged in a reverse manner to that shown in Fig. 1, that is, with the edges of the side slabs having the recesses arranged uppermost as shown at 35 19, so that the projections on the key members can be hung in the recesses, instead of hanging the side slabs on the projections as shown in Fig. 1.
- It will be clearly seen from the drawing, 40 that the depth of the recesses 13 and 18 is less than the thickness of the slabs, thus effectually inclosing the stud sections between the side walls and concealing the joints thereof.
- 45 Having thus fully described the invention, what is claimed is:—
1. A wall construction, comprising inner and outer walls each formed of a single line of side-slabs arranged in horizontal courses with staggered joints, each of said side-slabs being formed with recesses at their ends and which open only on the inner sides of the slabs, and through a portion of one longitudinal edge and a portion of the vertical edges, transverse key-slabs having beveled faced projections on each vertical edge at one side only to engage in the recesses in the side-slabs to support the side-slabs in alinement, and a concrete filling between each pair of transverse slabs and their projections to form stud sections at intervals throughout the length of the wall and lock the transverse slabs against the closed sides of the recesses.
  2. A wall construction, comprising inner and outer walls each formed of a single line

of side-slabs arranged in horizontal courses with staggered joints, each of said side-slabs being formed with recesses at their ends and which open only on the inner sides of the slabs and through a portion of one longitudinal edge and a portion of the vertical edges, each of said recesses having an undercut longitudinal side, transverse key-slabs having beveled faced projections on each vertical edge at one side only to engage in the recesses in the side-slabs to support the side-slabs in alinement, and a concrete filling between each pair of transverse slabs and their projections to form stud sections at intervals throughout the length of the wall and lock the transverse slabs against the closed sides of the recesses.

3. A wall construction, comprising inner and outer walls each formed of a single line of side-slabs arranged in horizontal courses with staggered joints, each of said side-slabs being formed with recesses at their ends and which open only on the inner sides of the slabs and through a portion of one longitudinal edge and a portion of the vertical edges, each of said recesses having an undercut longitudinal side, transverse key-slabs having beveled faced projections on each vertical edge to engage in the recesses in the side-slabs to support them in alinement, the thickness of the transverse slabs being less than the length of the recesses, and a concrete filling between each pair of transverse slabs and also engaging the undercut wall of the recesses in front of the transverse slabs, said concrete fillings forming stud sections at intervals throughout the length of the wall and lock the transverse slabs against the closed sides of the recesses.

4. A wall construction, comprising inner and outer walls each formed of a single line of side-slabs arranged in horizontal courses with staggered joints, each of said side-slabs being formed with a recess at each end and also a central recess, all of said recesses being open only on the inner sides of the slabs and each being provided with an undercut longitudinal side, transverse key-slabs having beveled faced projections on each vertical edge to engage the undercut sides of and in the end recesses of the side-slabs, and a concrete filling between each pair of transverse slabs to form stud sections at intervals throughout the length of the wall, said concrete filling engaging in the end recesses of the slabs in alternate courses and in the central recesses in the other courses.

5. In a wall construction, inner and outer walls formed of slabs, transverse key-slabs for connecting said walls together, the wall-slabs being formed with key receiving recesses on their inner sides only and provided with an undercut wall on one side of said

recesses, and said transverse key-slabs being formed with key projections of a thickness less than the length of said recesses and which are adapted to engage therein, and a
5 concrete filling between each pair of the transverse key-slabs, said filling also entering the portions of the recesses not filled by

the key projections, whereby the recesses serve as a keying means to receive at the same time both the key-projections and the 10 filling between the key-slabs.

In testimony whereof I affix my signature.

FRANK McMURRAY SAWYER.
